UNITED STATES PATENT OFFICE.

NICHOLAS S. VEDDER AND FRANCIS RITCHIE, OF TROY, NEW YORK,
ASSIGNORS TO NICHOLAS S. VEDDER, OF SAME PLACE.

DESIGN FOR COOKING-STOVE.

Specification forming part of Design No. 7,048, dated December 9, 1873; application filed September 12, 1873.
[Term of Patent 3½ years.]

To all whom it may concern:

Be it known that we, NICHOLAS S. VEDDER and FRANCIS RITCHIE, residents of the city of Troy, in the county of Rensselaer and State of New York, have jointly invented and produced a new and original ornamental Design for Cooking-Stoves, of which the following is a specification, reference being had to the accompanying engraving of a cooking-stove which embodies our said new design.

One part of our invention consists of the design for the ornament A for an oven-door panel, having its lower part extended forward of its upper portion, the said ornament being composed of the swelling middle portion, having thereon a branch with a flower and leaves, and surrounded by the combination of scroll-work ornamentations, of which the lower portion extends forward of and is broader than the upper part, with or without the forwardly-projecting scroll-branch b, all shaped and arranged together and upon the panel substantially as represented in the accompanying wood-cut or engraving.

Another part of our invention is the design for the oven-door, consisting of the ornament A, composed, shaped, and arranged on the panel of the door, as above specified, in combination with the panel-border D, composed of the outer convex molding e and the inner band f, having transverse angular grooves or flutes and a raised bead-molding along each edge, all substantially as represented in the aforesaid engraving.

Another part consists of the design for the door or panel at the end of the fire-chamber, composed of the ornament C, arranged on the middle portion of the plain rectangular panel, and having a four-sided central part surrounded by scroll-work ornamentation, in combination with the border D, surrounding the panel, and consisting of the outer convex molding e and the inner crimped fillet f, all shaped and disposed so as to appear substantially as represented in the aforesaid cut.

Another part consists of the design for the lower front door K, as distinguished by the upright oblong openings through its middle portion, and the border composed of the outermost

convex molding l, the adjacent concave molding m, the inner concavo-convex molding n, and the inside crimped or fluted band o, all shaped and arranged together so as to appear substantially as shown in the aforesaid engraving.

Another part consists of the design for the side plate G, as distinguished by the narrow lower portion of the plate extended forward of the main upper portion thereof, and the front end of the said lower extended portion inclined forward and upward and bordered by the compound molding having the upper part straight and the lower portion concave, in combination with the two oblong panels h h, arranged end to end, but apart from each other, and horizontally on the lower portion of the plate, and with a part of the forward panel upon that part of the plate which extends forward of the upper portion thereof, and each panel h having truncated corners i i i i and surrounded by the bead-molding j, and the whole shaped and disposed as represented in the aforesaid cut.

We do not claim the design for the legs, nor the design for the border D of the door-panels; and we do not claim a design for a side plate of a cooking-stove distinguished solely by its lower part being extended forward of its upper portion, with the front end of the extended lower part inclined forward and upward, and the upper part straight and the lower portion concave, and bordered by a compound molding; nor do we claim a design for a side plate of a cooking-stove having oblong panels h h, with truncated corners i and bead-molding borders j on the lower part thereof, when the forward panel and lower part of the plate do not extend forward of the upper portion of the plate.

What we claim as our joint invention is—

1. The design for the curved ornament A, composed as herein specified, and shaped and arranged upon a panel having its lower portion extended forward of its upper part, substantially as represented in the aforesaid engraving.
2. The design for the oven-door consisting of the ornament A, composed as described, and arranged on the plain surface of the panel, in combination with the panel-border D, composed of the outer convex molding e and the

inner band *f*, with transverse angular grooves or flutes and a bead-molding along each edge, substantially as shown and described.

3. The design for the door or panel at the end of the fire-chamber, consisting of the central ornament *C* and the border *D*, composed of the outer convex molding *e* and the crimped inner fillet *f*, all shaped and arranged on and around the plain rectangular surface substantially as represented in the aforesaid engraving.

4. The design for the lower front door *K*, as distinguished by the upright oblong openings therein, surrounded by a border composed of the convex molding *l*, concave molding *m*, concavo-convex molding *n*, and crimped fillet *o*, all shaped and arranged together as shown in the aforesaid cut.

5. The design for the side plate *G*, distinguished by the lower part extending forward of the upper portion, and the front end of the lower part inclined forward and upward, with the upper part straight and the lower part concave, and all bordered by the compound molding, in combination with the panels *h h*, bordered by the bead-molding *j* and having truncated corners *i*, and a part of the forward panel upon that part of the plate which extends forward of the upper portion, substantially as shown and described.

NICHOLAS S. VEDDER.
FRANCIS RITCHIE.
